BUCKING BAR CONTROL FOR RIVETING HAMMERS

Edward W. Stevens, Detroit, Mich., assignor to Chicago Pneumatic Tool Company, New York, N. Y., a corporation of New Jersey

Application February 4, 1944, Serial No. 521,023

11 Claims. (Cl. 78—48)

1

This invention relates to riveting apparatus assemblies fundamentally comprising a fluid actuated tool and a bucking bar cooperating therewith to set rivets, and more particularly to certain features of automatic bucking bar remote control mechanism for said tool.

An object of the present invention is to introduce an improvement related to the copending application Serial No. 467,531 of James A. Roberts, filed December 1, 1942 for Bucking bar control for riveting hammers, which has matured into Patent No. 2,375,691, granted May 8, 1945. The invention has a special but by no means exclusive application to aircraft riveting tools suitable for operation on light sheet metal.

The main object of this invention is therefore to facilitate riveting by providing a bucking bar mechanism for a fluid actuated riveting hammer or other tool having direct manual control, with improved means governing the height of the heads of the rivets to be set and operating automatically to stop the hammer when the predetermined height of a rivet has been produced.

Another very important object is to increase the speed and uniformity of the riveting operation by providing adjustable accurate control of the hammer from the bucking bar mechanism in such manner as to produce uniformly set rivets with substantial elimination of damaged work.

It is also an object to have associated with a pneumatic hammer, a bucking bar mechanism or assembly provided with a member which not only governs the height of the heads of rivets to be set, but positively prevents production of too flat or small rivet heads even when the bucking bar is held adjacent to the work for an unusually long time.

Other objects and the advantages inherent in the invention and accruing from its use in actual practice will appear more fully in detail as this specification proceeds.

The invention is illustrated in the accompanying drawings forming part hereof and in which:

Fig. 1 is a side elevation of a fluid actuated hammer in operative position against a work piece with a bucking bar mechanism operatively connected to the hammer and embodying control means for determining the height of the rivet heads intended to be set by the mentioned apparatus, portions of the apparatus being shown in section to disclose details of construction while the manual control lever is illustrated in active operating position;

Fig. 2 is an enlarged side elevation, for the most part in section, showing the bucking bar mechanism with the manual control lever in initial starting position ready to initiate a cycle of operation;

Fig. 3 is an end view of the same device as seen from the right in Fig. 2;

2

Fig. 4 is also an enlarged elevation of the bucking bar mechanism similar to that of Fig. 2 but showing the manual control lever in operated position and in released or neutralized condition;

Fig. 5 is a transverse section of the mechanism of Fig. 4 as taken on line 5—5;

Fig. 6 is another transverse section of the same taken on line 6—6 in Fig. 4; and

Fig. 7 is a fragmentary perspective view of the manual operating lever of the same mechanism.

In the riveting art the use of riveting assemblies of the present kind requires the services of two operators on opposite sides of the work who are occasionally hidden from each other, rendering each operator incapable of noting directly the movements of the other. In some assemblies used before the invention of Roberts in the copending application, the throttle valve for the fluid supply was arranged to be under the control of a single operator, either the riveter or the bucker, who would usually delay commencement of the hammering operation until certain that the other operator was ready. Occasionally it then happened that the hammer was started before the rivet was properly backed up or before the hammer was in proper operative position, which in either case would likely result in damaged work.

While the invention of said Roberts is designed to eliminate the mentioned disadvantages and facilitate the operation of setting a rivet to such an extent that it is unnecessary for the operators engaged in the work to see each other or to observe any special precautions in order to produce satisfactory and rapid work, the present invention is directed to improved means for positively determining a uniform height of the heads of the rivets intended to be set.

It is, of course, self-evident that when a large number of rivets are to be set, the time element involved is not only affected by the speed of operation as ensured by effective cooperation between the two operators, but also by the uniformity in the height and quality of the heads on the finished rivets. If some rivets are at first not sufficiently set during operation, necessitating repeated operation to bring them to uniform height with the rest, time is lost, and if set too much, they are defective and damage has resulted.

The present invention is designed to ensure that at all times the heads of the rivets will be set to a uniform height.

Hence, referring again to the drawings, a riveting assembly comprises a pneumatic hammer, generally indicated at 8 of a type favored in the aircraft industry for setting small aluminum and alloy rivets. The hammer assembly includes a cylinder 9 with an offset rigid handle 10 and houses a fluid operated motor provided with a

reciprocable piston 11 and means for directing pressure fluid alternately to the ends thereof, while the handle is formed with an air inlet port 12 and throttle means operating under the control of a trigger 13. The piston 11 acts as a hammer, delivering impacts to an anvil or rivet set 14 which extends beyond the front end of the cylinder for engagement with the work. The work or work piece, in this instance, is represented by a pair of overlapping plates generally indicated at 15 (hereinafter termed "the work") which are fastened together by rivets to form part of an airplane skin covering. Guide holes are first provided in the work to receive rivets 16, the same being disposed with preformed heads contacting with the work 15 on one side thereof and having shank portions projecting through to the opposite side. According to one method of riveting, anvil or rivet set 14 is pressed against the preformed head on the rivet while the shank portion is engaged on the opposite side of the work and during operation set as shown at 17 by a bucking bar 18 of a bucking mechanism generally indicated at 19. When the hammer is then started, percussive impulses are delivered to the work through the anvil 14 and are sustained by the bucking bar 18. As forward pressure is exerted by the bucking bar throughout the operation the reaction of the hammer blows serves to upset the shank of the rivet, a flat or oval head being thereby formed on the side of the work opposite to that occupied by the preformed head.

It is important that the skin surface of the work be not marred or scratched by a premature hammer action. Thus care must be exercised by the separate operators holding the hammer and the bucking mechanism that the ends of the rivet are initially properly engaged before the hammer is started. As a matter of precaution, the apparatus is designed to guard against mis-operation resulting from a lack of such engagement by placing the compressed air supply under the control of both the riveter and the bucker. The piston 11 can therefore not begin reciprocation until the operators of the hammer and bucking bar mechanism signify by releasing the air supply that their respective implements are in effective working position. Important as the features just mentioned may be for proper operation, it should be noted that it is a prominent feature of the invention to make it wholly unnecessary for the bucker to observe any special care in order to produce a uniform height of rivet head on all rivets set when using the present bucking bar mechanism.

The air inlet port 12 is part of a pressure fluid supply pasageway including passages 20 and 21 communicating through a bore 22. Within said bore 22 is a bushing 23 having ports registering respectively with passages 20 and 21. Communication between passages 20 and 21 is controlled by a trigger operated throttle valve 24 in bushing 23, said valve being pressed by a spring 25 to a seat 26 between the ported areas of the bushing and so normally prevents the flow of fluid to the passage 21 and thereby to the hammer cylinder. Valve 24 has a stem 27 extending upward through and beyond the bushing 23, the upper end of the stem underlying one arm of a lever 28 which is pivotally mounted at 29 within a recess in the handle 10 and is operatively engaged with the trigger 13. When the trigger is shifted rearward by the pressure of the finger of an operator the lever 28, rocking upon its pivot 29

unseats valve 24, whereupon air from inlet port 12 and passage 20 is allowed to flow through bushing 23 and into passage 21 whence it flows to the motor to initiate operation of the hammer.

Air under pressure is supplied to the inlet port 12 through a fitting in the form of an auxiliary valve housing 30 introduced between the inlet port 12 and a hose line 31 to facilitate control of the operation of the hammer by means of the invention. The auxiliary housing 30 has a tubular portion 32 extending into the inlet port 12 in threaded connection with a bushing 33. The body of the same housing 30 defines a chamber 34 receiving air from the hose line 31 and communicating with the interior of tubular portion 32 by way of a passage 35. Controlling the flow of air from chamber 34 to passage 35 is an auxiliary throttle valve 36, which has a valve head 37 disposed within chamber 34 while the valve stem 38 thereof extends through passage 35 and into a split projection 39 on the housing. The head 37 of valve 36 is adapted to occupy or engage with a valve seat 40 on the peripheral edge of passage 35 and thereby cut off the flow of fluid from chamber 34 to tubular portion 32 and inlet port 12. The supply of air to the hammer is therefore under the dual control of the throttle valve 24 and the auxiliary valve 36, either or both of which when closed will cut off the supply of fluid from the motor and so prevent operation of the hammer. The two valves 24 and 36 are actually arranged in series and thus provide the dual control of the operation.

The opening of valve 36 is accomplished by remote control from the bucking bar 18 by means of a Bowden type flexible cable 41 extending between the hammer 8 and the bucking mechanism 19 and made up of a wound sheath 42 and an inner wire or core 43 slidable within said sheath. The cable at one end is received in the split projection 39 of housing 30 and at its other end extends through a similar split clamping projection 44 on the bucking bar fitting in a transverse bore 45 in said bar. Clamping screws 46 and 47 in the respective split projections 39 and 44 serve to clamp the ends of the cable within the two implements. The core 43 is movable longitudinally within its sheath and arranged with one end projecting beyond the sheath, where it is secured to the stem 38 of valve 36 by soldering, brazing or welding. The other end of the same core projects upwardly in a counterbore 48 in the bucking bar and is capped by a plunger 49 secured thereto and located in said counterbore and normally projecting a short distance above the bucking bar. The counterbore 48 is of greater diameter than the bore 45 receiving the end of the cable sheath and forms a casing for a compression spring 51 surrounding the cable core beneath plunger 49 and tending to hold the latter resiliently in the raised initial position shown in Figs. 1 to 3 and causing a pull to be exerted on said cable core, thereby maintaining the auxiliary throttle valve in housing 30 normally closed.

The means included in the bucking bar mechanism or assembly for depressing the plunger and thereby opening the auxiliary throttle valve to allow pressure fluid to enter inlet port 12 from chamber 34 primarily consists of a manual operating lever 52 preferably formed of sheet metal of inverted U-shaped cross section with the sides 53, 53 bent down from the top web portion 54 and terminating in a pair of lugs 55 at the forward end thereof, pivotally mounted in a pair of op-

posite side recesses 56 on a pivot pin 57 in the bucking bar 18. Within the sides 53, 53 of lever 52 is a movable escape or release slide member 58. This latter is made of a metal strip bent back on itself to form upper and lower slide strips 59, 61 connected at one end by a web portion 62 and shiftably mounted upon a pair of cross rods 63 in such fashion as to straddle the latter, the slide member 58 being slidable longitudinally within sides 53 and top 54 of said manual lever. To the rear or outer end 64 of the manual lever 52 is fixed an interior guide rod 65 extending longitudinally forward in substantial parallelism with the top and sides toward the pivoted end of the manual lever and projecting slidably into the rear end or web 62 of the release slide member through an aperture 66 and supporting a coil spring 67 bearing against the rear end of said release slide member and thus tending to urge the latter forward. Upon the underside of the lever is fixed an inflexible plate 68 serving to assist in retaining the release slide member in place and more definitely to press upon the upper end of a lever return plunger 69 located in a limited bore 71 in the bucking bar and provided with a compression spring 72 tending to raise said plunger against said lever plate and thereby raise the lever to normal starting position in which the plunger cap 49 upon the cable core 43 is also in normal raised position with the auxiliary throttle valve 36 closed.

In the lower strip 61 of the release slide member is an aperture or gap 73 which is adapted to register with the upper end of the cable cap 49 in a manner now to be explained. When the riveter or hammer operator has placed the hammer 8 in operative position against the head of a rivet 16 and then manually presses the trigger or plunger 13 and thereby opens the throttle valve 24, the hammer will not begin to operate until certain other conditions are also present.

When the bucker who handles the bucking mechanism is about to cooperate with the riveter to set a rivet, he places the end of the bucking bar 18 more or less accurately against the shank end of rivet 16. During this movement a sleeve 74 adapted to surround the rivet first engages against the work 15 and is resiliently retracted upon the bucking bar by pressure until the latter makes contact with rivet 16 in a manner and for a purpose now to be explained. The mentioned sleeve is slidably mounted on the forward working end 75 of the bucking bar and has an expanded rear portion 76 surrounding a spring 77 engaging forwardly at one end against a shoulder 78 in said sleeve and rearwardly against a shoulder 79 on said bucking bar at the other end and resiliently urging the sleeve forward to project beyond end or forward portion 75 of the bucking bar.

To prevent accidental loss or undue displacement of the sleeve, a retaining pin 81 is secured in the forward portion 75 of the bucking bar with the upper end extending into a longitudinal slot 82 in said sleeve and thus limiting movement of the latter to the extent allowed by the pin in said slot. An aperture 83 in the bottom of the sleeve affords access in one position of the latter to the lower end of the pin when the same is to be removed for repairs or replacement of parts. Upon the rear of the enlarged portion 76 of the sleeve 74 is fixed a screw post 84 in which is mounted an adjustable screw 85 adapted to engage against the forward end 86 of the release slide member 58 in manual operating lever 52 in all positions of the

latter, a set screw 87 in said post serving to fix the adjustable screw 85 in any attained position of adjustment.

Thus, when the bucker is about to bring the bucking bar against the rivet 16, the first portion of the bucking mechanism which will make contact with the work as already explained is the end of the sleeve 74, and although the latter projects a distance beyond the working end 75 of the bucking bar, it is obviously quite simple for the bucker to locate said end of the bar on the rivet without loss of time or exercise of great care. When the device is moved toward the work 15 sufficiently to bring end 75 of bucking bar 18 into actual contact with the rivet as shown in Fig. 1, the sleeve 74 will be pushed in upon the bucking bar against the resistance of spring 77, and when the operator of said device depresses the manual lever 52 from the position of Figs. 1 to 3 to that of Figs. 4 and 5, the contact of the lower strip 61 of release slide member 58 within or beneath the manual lever with the plunger or cap 49 will cause the latter to be depressed, and this in turn immediately opens the auxiliary valve 36 in casing 30 of the hammer. The trigger operated throttle valve 24 having already been opened by the riveter, as already stated, the opening of valve 36 just mentioned immediately allows pressure fluid to flow to the piston 11 of the hammer, and start actual operation of the latter.

During this operation, as the riveting rapidly proceeds, the sleeve is gradually pushed further in upon the bucking bar by the latter following up the progressive shortening of the rivet until the rivet has been completely set as shown at 17 in Fig. 4. Such rearward movement of the sleeve is continuously transmitted to the release slide member 58 within lever 52 in opposition to spring 67 of the latter and produces a corresponding rearward travel of said member 58 until the aperture 73 in the bottom of the same begins to register with the cable plunger 49. At this instant the mentioned plunger, urged by its spring 51, immediately rises up into the aperture 73 directly above the same and by correspondingly pulling on the cable core 43, effects instant closure of auxiliary valve 36 in the hammer assembly and stops operation of the hammer. The time of subsequent closure of the throttle valve 24 by release of the trigger 13 by the rivet is of minor importance in the cycle of operation just described, and the two devices are therefore shifted by both operators to a new rivet for setting the same in a new cycle of operation.

The hammering operation is thus terminated automatically when the front end 75 of the buck bar 18 approaches within a predetermined distance of the work 15 and of the front extremity of sleeve 74. This distance, which corresponds to the height of the completed rivet, remains uniform in successive operations as long as the elements of the device remain in their adjusted position. To increase (or decrease) the height of the finished rivet, the adjustable screw 85 is turned to a more rearward (or more forward) position in post 84.

A slightly different starting of the cycle is not only possible but occurrence thereof is also likely to be more or less frequent, for it may well be that the bucker is ready before the riveter and by haste or misinterpretation of a signal and with the bucking mechanism in position, may depress the manual operating lever 52 to open valve 36 in the hammer mechanism before the latter is in position and the trigger 13 pressed by the

riveter to open throttle valve 24. Depressing said operating lever will not alone cause operation of the hammer, and will thus not occasion premature movement of any part of the assembly nor cause damage to the work piece involved, but actual operation is merely delayed until the riveter has the hammer anvil in place on the rivet head and then presses the trigger 13, when the hammer will operate and the cycle will proceed and be completed as previously described.

Manifestly, modifications are possible and may be resorted to, and parts may be altered in size or form and used without others, within the scope of the invention as defined in the appended claims.

What is claimed is:

1. A riveting assembly, comprising a fluid pressure operated hammer, a bucking bar, said hammer and said bar being carried by separate operators and adapted to engage a rivet on opposite sides of the work, and means causing the operation of said hammer to be under the control of the hammer operator in dependence upon independently operable remote control from the bucking bar in order to prevent damaging the rivet or the work by premature hammer operation, said means comprising a first fluid pressure control valve and local means associated with the hammer for opening said valve at will, a second fluid pressure control valve in series with said first valve and capable of being opened independently of the operation of the first valve, and mechanical operating means on said bucking bar capable of becoming automatically effective during operation to close said second valve upon production of a predetermined amount of set upon said rivet, said mechanical operating means on said bucking bar acting through a flexible cable comprising a sheath attached at one end to said hammer and at the other end to said bucking bar and containing a movable core extending into cooperative relation at one end with said auxiliary valve and at the other end extending to said hammer.

2. A riveting assembly, comprising a fluid pressure operated hammer, a bucking bar, said hammer and said bar being under separate control and adapted to engage a rivet on opposite sides of the work, supply means for conducting pressure fluid to said hammer, a throttle valve associated with said hammer for controlling the flow of pressure fluid through said supply means, an auxiliary valve for controlling the flow of fluid through the same supply means, said valves cooperating to cut off the flow of fluid to said hammer when either or both of said valves are closed, local operable means associated with said hammer for controlling said throttle valve, actuating means for said auxiliary valve including a flexible cable sheath extending between said hammer and said bucking bar and containing a movable core operable at one end as a movable plunger from said bucking bar and at the other end extending into cooperative relation with said auxiliary valve, operative means upon said bucking bar for moving said core and thereby opening said auxiliary valve, and movable means associated with said bucking bar capable of becoming automatically effective to neutralize said operative means and release said core in order to cause said auxiliary valve to be closed upon completion of a predetermined degree of set upon said rivet.

3. In a riveting assembly, a bucking bar adapted for cooperation with a fluid pressure oper-

ated hammer, supply means for conducting pressure fluid to said hammer, a control valve associated with said hammer for controlling the flow of the fluid through said supply means to the hammer, actuating means for said control valve including a flexible cable comprising a core and a sheath surrounding the same, the core being movable with reference to the sheath upon the application of pressure to an end thereof having one actuating portion thereof extending into cooperative relation with said valve and having another actuating portion associated with the bucking bar and movable with respect thereto, operable means upon said bucking bar for imparting movement to said actuating means and thereby opening said control valve, and a movable releasing member supported upon said bucking bar automatically effective during operation to disable said operable means and release the motion transmitting means and thereby cause said control valve to be closed upon completion of a predetermined amount of set upon said rivet.

4. A riveting assembly, comprising a fluid pressure operated hammer, a bucking bar, said hammer and said bar being carried by separate operators and adapted to engage a rivet on opposite sides of the work, supply means for conducting pressure fluid to said hammer, a throttle valve associated with said hammer for controlling the flow of fluid through said supply means, an auxiliary valve for controlling the flow of fluid through the same supply means, said valves cooperating to cut off the flow of fluid to said hammer when either or both of said valves are closed, local operable means associated with said hammer for controlling said throttle valve, actuating means for said auxiliary valve including a flexible motion transmitting means having one actuating portion extending into cooperative relation with said auxiliary valve and having another actuating portion associated with the bucking bar and movable with respect thereto, operable means upon said bucking bar for operating said motion transmitting means and thereby opening said valve, and a movable contacting member mounted on said bucking bar for engaging against the work in the vicinity of the rivet to be set, and a shiftable releasing member engaged by a portion of said contacting member and capable of neutralizing said operable means and releasing said motion transmitting means and thereby cause the auxiliary valve to be closed upon occurrence of a predetermined relative change in position between said bucking bar and contacting member caused during operation due to the progressive shortening of the rivet by the production of a predetermined amount of set upon said rivet.

5. A riveting assembly, comprising a fluid pressure operated hammer, a bucking bar, said hammer and said bar being carried by separate operators and adapted to engage a rivet on opposite sides of the work, supply means for conducting pressure fluid to said hammer, a throttle valve associated with said hammer for controlling the flow of fluid through said supply means, an auxiliary valve for controlling the flow of fluid through the same supply means, said valves cooperating to cut off the flow of fluid to said hammer when either or both of said valves are closed, local operable means associated with said hammer for controlling said throttle valve, actuating means for said auxiliary valve including a flexible motion transmitting means having one end portion extending into cooperative relation with

said auxiliary valve and having the other end portion associated with the bucking bar and movable with respect thereto, manually operable means upon said bucking bar including a depressible member mounted in effective position to move said other end portion of said motion transmitting means to open the auxiliary valve, resilient means tending to return said depressible member to initial position when released, a movable contact member slidably mounted upon said bucking bar for engaging against the work, and a shiftable releasing member associated with said depressible member and engaged by a portion upon said contact member in effective position to be shifted relatively to said depressible member and neutralize the latter with consequent release of the motion transmitting means and corresponding closure of the auxiliary valve upon occurrence of a predetermined relative change in position between said bucking bar and contact member due to the progressive shortening of the rivet caused during operation by production of a predetermined amount of set upon said rivet.

6. In a riveting assembly, a bucking bar adapted for cooperation with a fluid pressure operated hammer, supply means for conducting pressure fluid to said hammer, a valve for controlling the flow of fluid through the supply means, actuating means for said valve including a flexible motion transmitting means having one end portion extending into cooperative relation with said valve and having the other end portion associated with the bucking bar and movable with respect thereto, manually operable means upon the bucking bar including a depressible lever pivotally mounted in a position effective to move said other end portion of said motion transmitting means to open the valve, resilient means tending to return said motion transmitting means in closing direction to initial position of said valve to close the latter, a movable contact member slidably mounted on said bucking bar, resilient means tending to cause said contact member to project beyond the working end of the bucking bar to make direct contact with the work, said depressible lever also tending to be returned to initial position when released, and a shiftable releasing member associated with said depressible lever and engaged by a portion upon said contact member in effective position to be shifted relatively to said lever in order to neutralize the latter with consequent release of the motion transmitting means and closure of the valve upon occurrence of a predetermined relative change in positions between said bucking bar and contact member due to the progressive shortening of the rivet caused by the production of a finished setting upon said rivet.

7. A riveting assembly, comprising a fluid pressure operated hammer, a bucking bar, said hammer and said bar being carried by separate operators and adapted to engage a rivet on opposite sides of the work, supply means for conducting pressure fluid to said hammer, a throttle valve associated with said hammer for controlling the flow of fluid through said supply means, an auxiliary valve for controlling the flow of fluid through the same supply means, said valves cooperating to cut off the flow of fluid to the hammer when either or both of said valves are closed, local operating means associated with said hammer for controlling said throttle valve, actuating

means for said auxiliary valve including a flexible motion transmitting means having one end portion extending into cooperative relation with said auxiliary valve and having the other end portion associated with the bucking bar and movable with respect thereto, manually operable means upon the bucking bar including a depressible lever pivotally mounted in a position effective to move said other end portion of said motion transmitting means to open the auxiliary valve, resilient means tending to return said motion transmitting means in closing direction to initial position of said auxiliary valve, a movable contact member including a sleeve slidably mounted on said bucking bar, resilient means tending to cause a portion of said sleeve to project beyond the working end of the bucking bar to make direct contact with the work, resilient means also tending to return said lever to initial position when released, a shiftable releasing member slidably mounted on said lever so as to partake of the pivoting movements thereof and normally allow the lever upon depression thereof to impart movement to the motion transmitting means and thereby cause opening of the auxiliary valve, and a projecting portion upon said slidably mounted sleeve engaging said releasing member at least in depressed position of said lever and capable of neutralizing the effect of said lever in said depressed position with consequent release of the auxiliary valve upon occurrence of a predetermined change in relative positions between said sleeve and bucking bar due to the progressive shortening of the rivet caused during operation by production of a predetermined degree of set upon said rivet.

8. A riveting assembly according to claim 7, in which the releasing member is disposed within a portion of, and carried by, the pivotally mounted lever and has one end thereof directed toward the pivoted end of the lever and engaged by the projecting sleeve portion serving as a reaction point for shifting said member.

9. A riveting assembly according to claim 7, in which the releasing member has one end thereof disposed adjacent to the pivoted end of the lever and engaged by the projecting sleeve portion serving as a reaction point for shifting said member, and in which resilient means carried by the lever serves to urge said releasing member resiliently toward said projecting sleeve portion.

10. A riveting assembly according to claim 7, in which the releasing member normally forms the means upon the pivoted lever which directly engages with a projecting portion upon the end of the motion transmitting means, and in which said releasing member has a gap portion which registers with said projecting portion upon the end of said motion transmitting means in shifted position of said releasing member, said gap portion releasing said motion transmitting means and allowing the same by entrance of the projecting end thereof into said gap portion to return to initial position and close the auxiliary valve.

11. A riveting assembly according to claim 7, in which stop means are included for limiting movement of the sleeve to a predetermined range, and in which the projecting portion on said sleeve includes an adjustable abutment member.
